CLAIM

The ornamental design for an endplate for vibrating exercise roller, as shown and described.

DESCRIPTION

FIG. 1 is a front perspective view of the present design. FIG. 2 is a rear perspective view of the present design. FIG. 3 is a front elevation view of the present design. FIG. 4 is a top plan view of the present design. FIG. 5 is a bottom plan view of the present design. FIG. 6 is a left side elevation view of the present. FIG. 7 is a right side elevation view of the present design; and, FIG. 8 is a rear elevation view of the present design. In FIGS. 1-8, broken lines are shown to define boundaries around portions of the article which are not part of the claimed design.

1 Claim, 5 Drawing Sheets
